US00D853861S

(12) **United States Design Patent** (10) Patent No.: **US D853,861 S**
(45) Date of Patent: **** Jul. 16, 2019**

(54) **WRISTWATCH CASE**

(71) Applicant: **Pierre Nobs**, Volketswil (CH)

(72) Inventors: **Simon Husslein**, Zurich (CH); **Pierre Nobs**, Volketswil (CH)

(**) Term: **15 Years**

(21) Appl. No.: **35/504,391**

(22) Filed: **Aug. 1, 2017**

(80) **Hague Agreement Data**

Int. Filing Date: **Aug. 1, 2017**

Int. Reg. No.: **DM/097372**

Int. Reg. Date: **Aug. 1, 2017**

Int. Reg. Pub. Date: **Feb. 2, 2018**

(30) **Foreign Application Priority Data**

Feb. 16, 2017 (WO) 60666

(51) **LOC (11) Cl.** **10-02**

(52) **U.S. Cl.**

USPC **D10/30**

(58) **Field of Classification Search**

USPC D10/30, 32, 39, 37

See application file for complete search history.
